UNITED STATES PATENT OFFICE.

BERNE NADALL, OF KINGSTON-UPON-THAMES, ENGLAND, ASSIGNOR TO
THE LINOTYPE COMPANY, LIMITED, OF LONDON, ENGLAND.

DESIGN FOR A FONT OF TYPE ORNAMENTS.

SPECIFICATION forming part of Design No. 35,811, dated March 11, 1902.

Application filed January 25, 1902, Serial No. 91,292. Term of patent 14 years.

To all whom it may concern:

Be it known that I, BERNE NADALL, a citizen of the United States, residing at Kingston-upon-Thames, in the county of Surrey, England, have invented and produced a new and original Design for a Font of Type Ornaments, of which the following is a specification.

My design is clearly shown in the accompanying typographical impression, the representations of the type composing the font being numbered 1 and 2.

The main feature of the design presented by each of the types composing the font is that it includes a conventional outline illustration of two three-lobed leaves, the stems of which are connected by two compound-curved lines. The two compound-curved lines intersect with those forming the stems of the leaves in such a manner as to present the appearance of a band connecting the ends of said stems.

The design occupies a space substantially square, and in the form numbered 1 the outline leaf-like forms are arranged at the upper left-hand and lower right-hand corners of the

design, the stem-lines of such forms extending to the lower left-hand and upper right-hand corners, respectively. The form numbered 2 has these parts arranged in relatively reverse position—that is, the leaf-like forms ^{3d} are here placed in the upper right-hand and lower left-hand corners of the design, while the stems thereof extend to the lower right-hand and upper left-hand corners.

The several type ornaments herein described are of uniform design and are adapted to be grouped in various ways to form borders and other composite typographic ornaments.

Having thus described my invention, what ⁴⁰ I claim as new, and desire to secure by Letters Patent, is—

The design for a font of type ornaments, substantially as herein shown and described.

In testimony whereof I affix my signature ⁴⁵ in presence of two witnesses.

BERNE NADALL.
